HAND EMBROIDERY MACHINE

Filed Oct. 8, 1923

INVENTOR:

Manuel Humberto Pérez,

BY

P. C. Flores, ATTORNEY.

UNITED STATES PATENT OFFICE.

MANUEL HUMBERTO PÉREZ, OF SAN PEDRO SULA, HONDURAS.

HAND EMBROIDERY MACHINE.

Application filed October 8, 1923. Serial No. 667,342.

To all whom it may concern:

Be it known that I, MANUEL HUMBERTO PÉREZ, a citizen of the Republic of Honduras, residing at San Pedro Sula, in the Department of Cortez and Republic of Honduras, have invented new and useful Improvements in Hand Embroidery Machines, of which the following is a specification.

This invention relates to a hand embroidery machine for use in embroidering fabrics, and the primary object of the invention is to provide a device of this character which is readily movable dirigibly over the fabric while the needle is being manipulated, allowing embroidery work of any kind to be easily and expeditiously performed.

A further object of the invention is to provide an embroidery machine which can be manufactured and sold at a comparatively low cost and which is strong and durable in construction and rapid and efficient in action.

A still further object of the invention is to provide an embroidery machine designed to carry a number of spools of thread, so that selected threads of different sizes or colors may be used as desired.

A still further object of the invention is to provide novel means for guiding the needle and supporting and guiding the machine on the fabric, whereby the thread loops will be held smoothly pressed down against the fabric and their withdrawal or breakage or tearing of the fabric prevented.

The invention consists of the features of construction, combination and arrangement of parts, hereinafter fully described and claimed, reference being had to the accompanying drawing, in which:—

Figure 1 is a side elevation of a hand embroidery machine constructed in accordance with my invention.

Figure 2 is a vertical front-to-rear section through the same.

Figure 3 is a vertical transverse section through the spool carrying frame on line 3—3 of Figure 2.

Figure 4 is a vertical transverse section on line 4—4 of Figure 1.

Figure 5 is a longitudinal section on line 5—5 of Figure 2.

Figure 6 is a horizontal section on line 6—6 of Figure 2.

Figure 7 is a horizontal section on line 7—7 of Figure 1.

The machine comprising my invention consists of a supporting rod or standard 1 having a reduced threaded upper end or stem 2 and formed in its lower end with a bore or recess 3, the stem 2 receiving an internally threaded upper head or cap nut 4, while the recess 3 receives a tang or stem 5 extending upwardly from a lower head 6 and detachably fastened therein by a set screw or other suitable fastening device 7. A sleeve 8 surrounds the rod or standard 1 and is provided with a bore 9 contracted at its upper end, as shown at 10, to slidably engage the rod, the main body of said bore being of larger diameter than the rod, and a shoulder 11 being thereby provided at the juncture of the upper end of the bore 9 with its contracted portion 10. The bore 9 receives at its lower end a bushing 12, suitably fixed therein, and which carries a needle supporting head 13 having an opening for the reception of the upper end or shank portion of the needle 14 and provided with a set screw 15 for detachably fastening the needle in position. The sleeve 8 provides a handle, adapted to be reciprocated upwardly and downwardly on the rod or standard 1, for the purpose of transmitting reciprocating movements to the needle 14. A coiled spring 16 is enclosed in the bore 9 and surrounds the standard 1 between the shoulder 11 and the bushing 12, said spring being secured at its lower end to the standard 1 and at its upper end to the sleeve 8 and adapted to be compressed on the downward movement of the sleeve 8 to automatically return said sleeve to its elevated or starting position. The spring thus assists in the operation of the needle actuating device, and when the device is not in active service holds the handle or sleeve 8 and the needle 14 in a normally elevated position.

The head 6 has extending outwardly therefrom an arm 17, and said arm 17 is provided with a guide passage 18 through which the needle reciprocates and by which it is positively guided. Pivoted, as at 19, to the base of the head 6 is a presser-foot 20 comprising a plate adapted to ride in contact with the surface of the fabric 21 which is to be embroidered. This presser-foot is provided at its forward end with yoke arms 22 to receive a roller 23, is provided at its rear end with upturned guard lugs 24, and in advance of its pivot is coupled to the bar 110

17 by a coiled spring 25. Between the spring 25 and the roller 23, the presser-foot is provided with an opening 26 for the passage of the end of the needle carrying the thread 5 which is to be worked into the fabric. The roller 23 operates in conjunction with the presser-foot to adapt the machine to be moved easily over the fabric backwardly or forwardly or sidewise or in any direction, 10 and in conjunction therewith serves to press and hold the work threads smoothly down against the fabric and prevent the same from becoming loose, pulled out or broken or the fabric being torn, the presser-foot and roller 15 also serving to hold the engaged portion of the fabric firmly in position while the stitches are being made, so that embroidery work of firm and secure character and of first quality can be quickly performed. 20 The spring 25 serves by its expansive energy to hold the presser-foot and roller down to their work, and guard lugs operate to prevent the heel of the presser-foot from cutting or tearing the fabric, in the event of the 25 backward tilting of the device, and also serve to prevent objectionable downward tilting of the presser-foot and strain on the spring 25 when the machine is elevated from a work surface and not in use, as will be 30 readily understood.

A collar 27 surrounds the cap nut 4 and is provided with an arm 28 overlying the arm 17. These arms, in addition to the arm 17 serving as a guide for the needle, provide 35 supports for a spool carrying frame mounted upon the machine in proper working relation to the embroidering mechanism. This spool carrying frame comprises a pair of spaced parallel vertically disposed bars 29 40 and 30, the bar 29 being suitably secured at its upper and lower ends, in any durable and rigid manner, to the arms 17 and 28. Alined pairs of eyes or openings 31 are provided at intervals in the length of the bars 29 and 45 30 and the upper and lower pairs of openings thereof receive the reduced ends of cross-bars 32 whereby said bars 29 and 30 are coupled and the bar 30 supported from the bar 29. The reduced ends of the bars 50 30 are threaded for the reception of nuts 33, whereby the bars described may be readily and conveniently assembled and disassembled, and whereby the bar may be removed without disturbing the bar 29 or cross bars 55 32, for the purpose of applying or removing the thread spools. The other openings 31 in the bars 29 and 30 are adapted to receive the end spindles 34 of spools 35, which are thus rotatably mounted upon and between 60 the bars 29 and 30, the construction being such that any desired number of spools containing thread of the same or different sizes, different species or different colors may be held in position for ready and convenient 65 use, and so that the thread from any desired

spool may be threaded through the needle for use. The construction described provides an arrangement of the spool carrier frame and spools, which are permanently mounted upon the machine, whereby embroidery work 70 using different kinds of threads or threads of different colors may be employed in a quick and convenient manner for use on the same or different pieces of fabric which are to be embroidered at any time. Springs 75 36 suitably fastened on the spool carrier frame bars 29 and 30 are arranged to bear against the flanges of the spools and to exert sufficient spring frictional pressure thereon to prevent the spools from casual turning 80 and allowing the thread to unwind, while at the same time permitting the thread to wind with sufficient freedom to feed the needle in its operations.

In the use of the device, the thread is led 85 from any desired spool down through the eye of the needle, and after the needle has been thus threaded the device is placed upon the fabric to be worked with the presser-foot 20 arranged thereon, and then, as the 90 device is moved as required over the fabric, the handle 8 is reciprocated up and down, resulting in the formation by the needle of thread loops in the fabric along the lines of the intended design, the thread loops lying 95 close to one side of the fabric and the projecting portions at the opposite side of the fabric being trimmed off in the usual way. The handle is so formed that the tool may be 100 operated and guided simultaneously by the one hand of the operator engaging said handle, and manipulated back and forth over the fabric while the needle is being operated to produce the embroidery work. This 105 allows any design to be quickly, accurately and conveniently followed and, as a result of the construction of the presser-foot and its cooperating parts set forth, work of the highest quality may be produced.

It will be seen from the foregoing description that the tool is composed of a comparatively small number of working parts, the vital portions of which are largely concealed and protected from injury, and that their 110 construction and mode of assemblage allows the parts to be easily and conveniently assembled for the production of the machine and disassembled for cleaning, repairs, replacements or other purposes. These and other advantages will be apparent, in addition to those stated, to those versed in the art 115 without a further and extended description.

Having thus fully described my invention, I claim:

1. A hand embroidery machine comprising 125 a standard, a reciprocatory sleeve on said standard having a bore of larger diameter than the standard and contracted at its upper end to engage the standard and provide a shoulder, a bushing fitted in the lower end 130

- of the bore and engaging the standard and provided with a needle carrying head, a cap nut engaging the upper end of the standard and forming a stop to limit the upward movement of the sleeve, a coiled spring surrounding the standard and enclosed in the sleeve between the shoulder and bushing, a presser-foot carried by the lower end of the standard and having a needle opening therein, an arm carried by the standard above said presser-foot and having an opening therein, and a needle carried by the head and movable through said openings in the arm and presser-foot.
- 5 15. 2. A hand embroidery machine comprising a standard, a sleeve mounted to reciprocate upon the standard, an arm carried by the lower end of the standard and having a needle guide opening therein, a presser-foot pivoted to the standard beneath said arm, said presser-foot being pivoted at or adjacent its rear end and having a roller at its forward end and a needle opening lying adjacent to and in rear of said roller, a
- 20 25 needle carried by the sleeve and arranged to reciprocate through the openings in the arm and presser-foot, and an expansion spring disposed between and connected with the arm and presser-foot on a line between the needle openings therein and the vertical plane of the pivot of the presser-foot.
- 30 35 3. A hand embroidery machine comprising a standard, a presser-foot carried by the standard, a handle mounted to reciprocate on the standard, a pair of superposed arms carried by the standard, the lower one of
- said arms having an opening therein overlying the presser-foot, spool supporting means carried by said arms, and a needle actuated by the handle and movable through the opening of said lower arm.
4. A hand embroidery machine comprising a rod or standard having a threaded stem at its upper end and a socket at its lower end, a reciprocating sleeve on said standard having a bore of larger diameter than the standard and contracted at its upper end to engage the standard and provide a shoulder, a bushing fitted in the lower end of the bore and engaging the standard and provided with a needle carrying head, a needle carried by said head, a cap nut engaging the threaded stem of the standard and forming a stop to limit the upward movement of the sleeve, a head having a stem fitted in the socket in the lower end of the standard, and an arm carried by said head and arranged above the presser-foot and having a guide opening for passage of the needle.
5. A hand embroidery machine comprising a standard, embroidery mechanism mounted on the standard, arms supported by the standard, one of said arms having a guide opening for the needle of the embroidery mechanism, a spool carrying frame comprising vertical bars, one of said bars being fixed to said arms, cross-bars detachably coupling said vertical bars, and spools having spindles journaled in said vertical bars.

In testimony whereof I affix my signature.

MANUEL HUMBERTO PÉREZ.
